(57) **CLAIM**

The ornamental design for a compartment assembly for a refrigerator, as shown and described.

DESCRIPTION

FIG. 1 is a top right perspective view of a compartment assembly showing our new design mounted on a door liner of a refrigerator;

FIG. 2 is an enlarged, top right perspective view of the compartment assembly of the invention;

FIG. 3 is a front elevational view of the compartment assembly of FIG. 2;

FIG. 4 is a rear elevational view of the compartment assembly of FIG. 2;

FIG. 5 is a right side elevational view of the compartment assembly of FIG. 2;

FIG. 6 is a left side elevational view of the compartment assembly of FIG. 2;

FIG. 7 is a top plan view of the compartment assembly of FIG. 2;

FIG. 8 is a bottom plan view of the compartment assembly of FIG. 2; and,

FIG. 9 is a top right perspective view of the compartment assembly of the invention, similar to that of FIG. 2, but depicting a cover of the compartment assembly in an open condition.

The broken lines showing the refrigerator in FIG. 1 are for illustrative purposes only and form no part of the claimed invention.
